PIPE BENDER

Siegmund Mandl, Milwaukee, Wis., assignor to
 Blackhawk Mfg. Co., Milwaukee, Wis., a corporation of Wisconsin

Application July 25, 1942, Serial No. 452,317

10 Claims. (Cl. 153—40)

The present invention relates generally to improvements in the art of longitudinally bending elongated elements, and especially relatively thin walled tubes or pipes, to definite or predetermined curvature and without distorting the cross-sectional shapes of the hollow elements during the bending operations.

An object of the invention is to provide a new and useful tube or pipe bender which is simple in construction and efficient in operation.

Many different types of tube or pipe benders have heretofore been proposed and used with varying degrees of success, and in some of these prior devices hydraulic pressure was utilized to actuate the mechanisms and the units were of a relatively portable nature. In one of these prior portable hydraulic pipe benders, links having rollers journalled in their outer ends, were pivotally suspended from the cylinder of a hydraulic ram, and the piston of this ram had a segment pivotally attached thereto and disposed between the links and rollers. This segment was provided with a curved pipe bending surface formed eccentrically with respect to its supporting pivot, and the portions of the segment adjacent to the curved pipe engaging surface were adapted to roll in direct contact with a rectilinear follow bar which also engaged the pipe and advanced along the rollers during each bending operation. The lengths of pipe were gripped by a clamp carried by the segment near one end of the curved surface, and while this pipe bender was relatively satisfactory for certain limited uses, it was rather complicated and could not be readily adjusted to co-operate with pipes having different diameters.

It is therefore a more specific object of my present invention to provide an improved pipe bending assemblage of the above-described type, which is simpler and more durable in construction, and which can be quickly and conveniently adapted to fit various sized pipes.

Another specific object of the invention is to provide a tube or pipe bending unit which is especially adapted to bend relatively thin walled tubing to desired curvatures with minimum distortion of the cross-sectional shape of the tubes.

A further specific object of this invention is to provide a sturdy and compact hydraulically actuated portable pipe bender, wherein the bending force is most effectively applied to the work with minimum friction loss.

Still another specific object of my invention is to provide a strong and powerful pipe bending device operable by means of a relatively small

hydraulic ram and in any desired position, and which can be manufactured and sold at moderate cost.

These and other objects and advantages of the invention will be apparent from the following detailed description.

A clear conception of the features constituting the present improvement, and of several typical embodiments of the invention in commercial pipe benders, may be had by referring to the drawings accompanying and forming a part of this specification wherein like reference characters designate the same or similar parts in the various views.

15 Fig. 1 is a side elevation of a hydraulically actuated pipe bender equipped with a bender segment for small diameter pipe, portions of the assemblage having been broken away;

20 Fig. 2 is an end view of the pipe bending unit of Fig. 1;

Fig. 3 is a fragmentary end view of a similar pipe bending assemblage, equipped with a rotary rigid follower instead of a bar follower as in Figs. 1 and 2;

25 Fig. 4 is a side elevation of a somewhat modified hydraulically actuated pipe bender equipped with a bending segment for large diameter pipe;

Fig. 5 is a fragmentary end view of the bending unit of Fig. 4; and

30 Fig. 6 is a fragmentary end view similar to that of Fig. 3, but equipped with a rotary resilient or flexible follower instead of a follow bar.

While the invention has been shown and described herein as having been specifically embodied in relatively small portable pipe benders operable by means of hydraulic rams detachably associated directly with the bending mechanisms and supplied with liquid under pressure from manually operable pumps through flexible conduits, it is not my desire or intent to thereby unnecessarily restrict the scope or utility of the improvement.

Referring especially to Figs. 1 and 2 of the drawings, the improved hydraulically actuated portable pipe bender shown therein, comprises in general, a rigid frame 8 having a threaded socket 9 at one end and a bearing or reaction roller 10 journalled for rotation on a transverse pin 11 detachably secured to its opposite end, and also having a series of aligned sets of holes 12, 12', 12'' formed in the medial frame portion with the axes of the holes out of the common plane of the axes of the socket 9 and pin 11; a pipe bending member or segment 13 swingable

upon a transverse pivot pin 14 which is detachably and interchangeably co-operable with the holes 12 of any of the three sets, and having an arcuate pipe engaging groove or surface 15 formed concentric with the axis of the pin 14 and parallel flanges 16 on the opposite sides of the groove surface 15; a U-shaped pipe gripping element or clamp 17 pivotally secured to the segment 13 near one end of the surface 15 and flanges 16 by means of a pin 18; an elongated rectilinear follow bar or follower 19 having straight pipe engaging grooves 20, 21 of different curvature in the opposite sides thereof, one of which is co-operable with a pipe held by the clamp 17 while the opposite face of the bar is simultaneously co-operable with and movable along the bearing roller 10; an anti-friction roller 22 journaled for rotation upon a pin 23 secured to the segment 13 between the pivot pin 14 and the groove surface 15, remote from the clamp 17; and a hydraulic ram having a cylinder 24 fixedly but detachably secured to the socket 8, and also having a reciprocable plunger member or piston 25 slidable within the cylinder 24 and provided with a flat face 26 loosely engageable with the roller 22 and across which the latter is adapted to ride.

The rigid frame may either be formed of one piece by casting, or of several pieces firmly united by welding, and this frame should be of durable construction in order to withstand the stresses to which it is normally subjected. Although the bearing roller 10 is readily removable from the frame 8 upon withdrawal of its journal pin 11, such removal is not necessary even when adapting the pipe bending mechanism to pipes of different diameters as hereinafter described. The grooved work engaging segment 13 should also be of rigid and durable construction, and since the grooved surface 15 is formed concentric with the axis of the segment fulcrum or suspension pin 14, this surface 15 as well as the adjacent flanges 16 can be readily dressed or finished with utmost accuracy on a lathe or boring mill.

While but one segment 13 adapted to co-operate with pipe of relatively small diameter and swingable on a rather short radius about the axis of the holes 12 nearest the fixed end roller 10, is shown, the pipe bending outfit of Figs. 1 and 2 should be provided with three progressively larger segments 13 having correspondingly longer radii and larger grooves at their curved surfaces 15, and these additional segments 13 should be formed for proper coaction with suitably formed followers 19 adapted to fit the larger pipes. The end of the follower 19 nearest the clamp 17, should preferably be provided with a taper 19' in order to permit the follower 19 to assume a position corresponding to the final slightly elliptical cross-section of the bent pipe; and when the follower 19 is to be reversed for co-operation with different size piping, a tapered surface 19' should also be provided adjacent to the groove 20. As shown, the bar follower 19 has opposite grooves 20, 21 adapted to co-operate with two of the interchangeable segments 13 by reversing the follower 19, and another bar follower 19 having a pipe engaging groove of still greater curvature should be provided for co-operation with the largest of the three segments 13.

In order to interchange these three segments 13, it is only necessary to remove the fulcrum pin 14 from one set of aligned holes 12, 12', 12'' and from the segment 13 coacting therewith, and to insert this same pin 14 within another set

of the receiving holes and another of the segments, without disturbing the rest of the mechanism. The bar follower 19 may then be reversed so as to cause the groove 21 thereof to face the segment groove 15, or the additional bar follower (not shown) may be applied, in order to insure proper coaction of the segment 13 and follower 19 with the particular size of pipe which is to be bent.

Each quadrant segment 13 has a pipe gripping element or U-shaped clamp 17 pivotally attached thereto near the corresponding ends of the grooved surface 15 and flanges 16 thereof, by means of a pivot bolt or pin 18; and the contour of this clamp 17 is such that a pipe 27 shown in dot-and-dash lines in Figs. 1 and 2, may be readily inserted between the surface 15 and follower 19 within the clamp, before the segment 13 is engaged by the ram piston 25. However, when the segment 13 is swung about its fulcrum pin 14 in a clockwise direction as viewed in Fig. 1, the clamp 17 will tend to swing in a counter-clockwise direction about its pivot pin 18, and will thus firmly grip the pipe 27 and clamp the same into the adjacent end of the groove 15, and will thereby cause the pipe to advance with the segment 13. While the internal surface of the clamp 17 is preferably truly cylindrical, the coacting grooves 15, 20 of the segment 13 and follower 19 may be shaped to snugly fit the final slightly elliptical cross-sectional shape of the pipe 27 when bent, and in order to insure snug coaction, the follower 19 when in engagement with the bearing roller 10 may also be separated from the segment periphery or curved surface by spaces 28.

Each bending member or segment 13 also carries an anti-friction roller 22 disposed remote from the clamp 17 thereon, and this roller 22 is journaled upon a pin 23 and is adapted to ride back and forth across the plane face 26 of the ram piston 25 when the segment 13 is being swung about the fulcrum pin 14 by the ram plunger. The cylinder 24 of the actuating ram is adapted to be detachably secured to the threaded socket 9 of the rigid frame 8; and the piston 25 which is movable within the cylinder 24 by hydraulic pressure created by a pump communicating with the cylinder through a flexible conduit, is adapted to be withdrawn from contact with the roller 22 in order to permit interchangeable application of the several segments 13 of different sizes to the frame 8.

During normal operation of the pipe bending unit shown in Figs. 1 and 2, the hydraulic ram should first be manipulated to withdraw the piston 25 slightly from the roller 22, and the piece of small diameter tube or pipe 27 should be applied to the segment 13 and clamp 17 as indicated in Fig. 1 with the rectilinear bar follower 19 positioned as shown. The ram should then be actuated to cause the piston 25 to engage and move the roller 22 toward the bearing roller 10, whereupon the clamp 17 will firmly grip the adjacent portion of the pipe 27 and will cause the pipe to advance with the revolving segment 13. As the piston 25 continues its outward movement, the segment 13 continues to revolve and the bar follower 19 will then be advanced with the segment 13 and along the roller 10. This simultaneous advancement of the segment 13, follower 19 and pipe 27 will cause the pipe to be bent around and along the arcuate groove 15 of the segment 13 while being slightly distorted into the elliptical cross-sectional shape shown in Fig.

2. During this bending operation the peripheral side flanges 16 of the segment 18 will prevent lateral displacement of the follower 19, and the follower may be initially separated from the curved surface of the segment 18 by spaces 28 and need not contact the segment. When the bending operation has been completed, the movement of the ram piston 26 may be reversed, and the segment 18 and bar follower 19 may thereafter be returned to the position shown and the bent pipe may be withdrawn from the clamp 17. If it is desired to bend pipe 27 of larger diameter and to a larger radius of curvature, the segment 18 may be quickly replaced by a larger segment with the fulcrum pin 14 disposed in either set of holes 12', 12'', and the follower 19 may also be reversed or replaced by another having a groove properly shaped to fit the larger pipe.

While the follower 19 of Figs. 1 and 2 is of the rectilinear bar type, this follower may also be replaced by a rotary follower 29 such as shown in Fig. 3. The rotary follower 29 has a peripheral groove 30 formed to fit the final shape of the pipe 27 after bending thereof, and is journaled on a transverse pin 31 which may be substituted for the pin 11 of Fig. 1. The periphery of the rotary follower 29 may also be separated from the periphery of the segment 18 by spaces 28, as in the case of the follow bar, and this modified assemblage will operate in a manner similar to that of the device shown in Figs. 1 and 2. During the bending operation, the rotary follower 29 will revolve upon the pin 31 in a direction opposite to the direction of revolution of the segment 18, and the follower 29 will constantly retain the pipe 27 in snug engagement with the grooved surface 15 of the segment 18.

Referring specifically to the modified pipe bender shown in Figs. 4 and 5, this unit is quite similar to that shown in Figs. 1 and 2 except for various details of construction of the mechanism. In order to obtain better application of the pressures and distribution of the stresses when bending pipes 27 of different sizes, the main frame 32 of the modified assemblage has been formed to position the bearing roller 10 out of the line of movement of the ram piston 26; and the sets of holes 12, 12', 12'' for interchangeably receiving the fulcrum pin 14 of the modified segment 33, have been re-enforced by plates 34 punched from openings 35 in the opposite side walls of the frame 32 and welded to these walls adjacent to the holes. The modified segments 33 have also been additionally re-enforced, and while the pipe clamp 17 is the same as previously described, the anti-friction roller 22 has been located with reference to the fulcrum pin 14 so that this roller will travel nearer to the central axis of the actuating plunger 25 when the bending operation is being completed and maximum force is being applied. The rectilinear bar follower 36 of the modified structure is provided with but a single pipe engaging recess 37 which is co-operable with the peripheral curved pipe confining recess 38 of the segment 33, and the modified bending outfit should again be provided with three independent segments 33 and bar followers 36 of different sizes, adapted to coact with different sizes of pipes. The journal pin 41 which rotatably supports the follower engaging roller 10 of the modified structure, is of special construction, and this modified pin 41 has an integral central eccentric 42 and an integral serrated portion 43 adjacent to one end of the eccentric 42, which is rotatably adjustable within

a removable bushing 44 having a serrated hole formed centrally therein. Upon release of the clamping nuts 45 at the opposite ends of the pin 41 and which normally clamp this pin in adjusted position, the pin may be shifted to the left as viewed in Fig. 5, sufficiently to release the serrated portion 43, and subsequently revolved to cause the eccentric 42 to move the roller 10 toward or away from the segment 33, thus making it possible to cause the single roller 10 to properly co-operate with the followers 37 and segments 33 at all times. The pins 41, 14 are readily removable to release the roller 10 and the segments 33 respectively, by merely removing the retaining nuts. The operation of the modified pipe bender of Figs. 4 and 5 is obviously the same as that of Figs. 1 and 2, and both benders are adapted for use in bending pipes of three different diameters.

20 In Fig. 6, I have shown a modified rotary follower 39 which may be utilized in substitution for the followers 19, 29, 36 of the previously described pipe benders. The flexible or resilient cylindrical follower 39 is confined between metal side plates 40 and is journaled for rotation in the frame 32 by means of a transverse pin 31, and this follower 39 may be formed of relatively hard but resilient rubber or the like. The periphery of this roller follower 39 is normally cylindrical or approximately so, but when the follower 39 engages a pipe 27 to force the same into the segment groove 38, it will distort to the shape of the adjacent contour of the pipe 27 without indenting the latter. This type of follower 39 will automatically distort to snugly fit any size of pipe 27 and need not be replaced when the segments 33 are interchanged; and the side plates 40 and flanges 16 of the segments 33 will aid in causing the distorted portion of the follower 39 to hug the pipe 27.

40 From the foregoing detailed description of the construction and operation of my improved pipe bending unit, it will be apparent that the invention provides a pipe bender which is extremely simple and compact in construction and which is highly efficient in actual use. The improved mechanism comprises a relatively few simple and durable parts which can be readily manufactured and assembled, and the improved structure can be readily interchanged so as to properly coact with pipes having different diameters. The use of the rotary followers 29, 39 additionally simplifies the assemblage and reduces the bulk thereof, and the use of the flexible or resilient follower 39 of Fig. 6 further reduces the number of parts necessary in order to adapt the bender to pipes of different sizes, to a minimum. The modified eccentric pin 41 of Figs. 4 and 5, also makes it possible to adjust the reaction roller 10 so as to insure proper coaction between the follower and the bending segment. The modified assemblage of Figs. 4 and 5 also has the advantage of permitting convenient bending of the pipes 27 through longer distances than is possible with the embodiment of Figs. 1 and 2. With the structure of Figs. 4 and 5, pipes can readily be bent through arcs greater than ninety degrees when either large or small segments 33 are used, and the angular disposition of the frame with respect to the ram combined with the location of the axes of the holes 12, 12', 12'' in a common plane with the axis of the pin 41 facilitates such long bending. The entire pipe bending mechanism can be associated with a standard ram of the portable type, operable from a remote point with the aid of a pump connected to the ram by flex-

ible conduits, and the structure is adapted to produce successive bends of uniform radius and without undesirably distorting the cross-section areas of the pipes. The new pipe bender can be manufactured and sold at relatively moderate cost, and has proven highly successful in actual use. While the elliptical shape of the coacting grooves is relatively unimportant, the initial tapering of the bar followers is vitally important.

It should be understood that it is not desired to limit this invention to the exact details of construction, or to the precise mode of use, herein shown and described, for various modifications with the scope of the appended claims may occur to persons skilled in the art.

I claim:

1. In combination, a rigid frame having a transverse pivot pin mounted thereon, a segment swingable upon said pin and having a curved pipe engaging surface formed concentric with the pivot pin axis, a pipe engaging follower adapted to retain the pipe in contact with said segment surface during bending of the pipe, means for causing the pipe to positively advance about said axis with said segment, and a hydraulic ram having a piston provided with an end surface abutting loosely against and slidably co-operable with said segment, said piston being movable toward the segment at a point between said axis and said pipe engaging surface to swing the segment about said pin.

2. In combination, a rigid frame having a transverse fulcrum thereon, a segment swingable about said fulcrum and having a curved pipe engaging surface formed concentric with the fulcrum axis, a pipe engaging follower adapted to retain the pipe in contact with said segment surface during bending of the pipe, means for positively causing the pipe to advance about said axis with said segment, and a reciprocable plunger member movable with respect to said frame toward said segment at a point between said axis and said pipe engaging surface to swing the segment about said fulcrum, said member having a transverse end surface loosely abutting against and slidably coacting with said segment.

3. In combination, a rigid frame having a transverse fulcrum thereon, a segment swingable about said fulcrum and having a curved pipe engaging surface formed concentric with the fulcrum axis, a pipe engaging follower adapted to retain the pipe in contact with said segment surface during bending of the pipe, means for positively causing the pipe to advance about said axis with said segment, a reciprocable plunger member movable with respect to said frame toward said segment at a point between said axis and said pipe engaging surface to swing the segment about said fulcrum, said member having a transverse end surface loosely abutting against and slidably coacting with said segment, and a roller carried by said segment and coacting with said member surface to provide an anti-friction bearing at the zone of said sliding coaction.

4. In combination, a rigid frame having a transverse fulcrum thereon, a segment swingable about said fulcrum and having a curved pipe engaging surface formed concentric with the fulcrum axis, a pipe engaging follower adapted to retain the pipe in contact with said segment surface during bending of the pipe, a clamp carried by said segment at one end of said curved surface and being engageable with the pipe near the corresponding end of said follower to positively cause the pipe to advance about said axis with

the segment, and a reciprocable plunger member movable upon said frame toward said segment at a point between said axis and said pipe engaging surface to swing the segment about said fulcrum, said member having a transverse plane end surface loosely abutting against and slidably coacting with said segment.

5. In combination, a rigid frame having a transverse fulcrum thereon, a segment swingable about said fulcrum and having a curved pipe engaging surface formed concentric with the fulcrum axis, a pipe engaging follower adapted to retain the pipe in contact with said segment surface during bending of the pipe, a clamp carried by said segment at one end of said curved surface and being engageable with the pipe near the corresponding end of said follower to positively cause the pipe to advance about said axis with the segment, a reciprocable plunger member movable upon said frame toward said segment at a point between said axis and said pipe engaging surface to swing the segment about said fulcrum, said member having a transverse plane end surface loosely abutting against and slidably coacting with said segment, and a hydraulic cylinder carried by said frame and within which said plunger member is movable by fluid pressure.

6. In combination, a rigid frame having a transverse fulcrum thereon, a segment swingable about said fulcrum and having a curved pipe engaging groove formed concentric with the fulcrum axis, a follower having a rectilinear pipe engaging groove adapted to retain the pipe in contact with said segment groove during bending of the pipe, means for positively causing the pipe to advance about said axis within said grooves, and a reciprocable plunger member movable upon said frame toward said segment at a point between said axis and said pipe engaging groove to swing the segment about said fulcrum, said member having a transverse end surface loosely abutting against and slidably coacting with said segment.

7. In combination, a rigid frame having a transverse fulcrum thereon, a segment swingable about said fulcrum and having a curved pipe engaging groove formed concentric with the fulcrum axis, a follower having a rectilinear pipe engaging groove adapted to retain the pipe in contact with said segment groove during bending of the pipe, means for positively causing the pipe to advance about said axis within said grooves, and a reciprocable plunger member movable upon said frame toward said segment at a point between said axis and said pipe engaging groove to swing the segment about said fulcrum, said member having a transverse end surface loosely abutting against and slidably coacting with said segment, and the end of said follower nearest said means being gradually longitudinally tapered to cause the follower to be urged toward the segment groove as the pipe bending operation proceeds.

8. In combination, a rigid frame member having a transverse pivot pin mounted thereon, a segment swingable upon said pin and having a curved pipe engaging surface formed concentric with the pivot pin axis, a pipe engaging follower adapted to retain the pipe in contact with said segment surface during bending of the pipe, clamping means for causing the pipe to positively advance about said axis with said segment, a ram having a piston provided with an end surface loosely engaging and slidably co-operable with said segment, said piston being movable toward the segment at a point between said axis and said

pipe engaging surface to swing the segment about said pin, and means for effecting adjustment of said pin relative to said rigid frame in order to accommodate segments having different radii.

9. In combination, a rigid frame having thereon a fixed fulcrum and a reaction element spaced from the fulcrum, a rigid segment swingable upon said fulcrum and having an arcuate pipe engaging groove remote from the fulcrum movable past said element about said fulcrum relative to said frame, a pipe clamp carried by said segment for advancing a pipe coaxing with said groove about said fulcrum and past said element, and an elongated follower constantly movable with said segment past said reaction element and being progressively engageable with successive portions of the pipe and segment groove, the end of said constantly advancing follower nearest said clamp being gradually tapered in the direction of movement thereof and the tapered portion being movable past and in contact with said element to cause the constantly advancing follower to approach the segment groove as the pipe bending operation proceeds.

10. In combination, a rigid frame having thereon a fixed fulcrum and a reaction roller spaced from the fulcrum, a rigid segment swingable upon said fulcrum and having an arcuate pipe engaging groove remote from the fulcrum movable past said roller, means for swinging said segment about said fulcrum relative to said frame, a pipe clamp carried by said segment for advancing a pipe coaxing with said groove about said fulcrum and past said roller, and an elongated follower constantly movable with said segment past said reaction roller and being progressively engageable with successive portions of the pipe and segment groove, the end of said constantly advancing follower nearest said clamp being gradually tapered in the direction of movement thereof and the tapered portion being movable past and in contact with said roller to cause the constantly advancing follower to approach the segment groove as the pipe bending operation proceeds.

SIEGMUND MANDL.
